No. 36,723.

Patented January 5, 1904.

UNITED STATES PATENT OFFICE.

ROBERT E. FISHER, OF PROVIDENCE, RHODE ISLAND, ASSIGNOR TO SMITH BROTHERS, OF PROVIDENCE, RHODE ISLAND, COPARTNERS.

DESIGN FOR A CHARM OR SIMILAR ARTICLE.

SPECIFICATION forming part of Design No. 36,723, dated January 5, 1904.

Application filed December 12, 1903. Serial No. 184,994. Term of patent 3½ years.

To all whom it may concern:

Be it known that I, ROBERT E. FISHER, a citizen of the United States, residing at Providence, in the county of Providence and State of Rhode Island, have invented a certain new, original, and ornamental Design for a Charm or Similar Article, of which the following is a specification, reference being had therein to the accompanying drawing.

The drawing represents the obverse and reverse of a charm embodying my new design.

What I claim is—

The ornamental design for a charm or similar article, as herein shown.

ROBERT E. FISHER.
